UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,944, dated June 24, 1890.

Application filed April 15, 1890. Serial No. 348,116. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part hereof.

10 Referring to said drawing, A represents the body of the handle, B the top or head, and C the base thereof. The body part is convex, and at the same time decreasing in diameter from its middle part downward, and formed 15 with a series of depressed faces D, arranged slightly on a spiral, as shown. These faces D have ornamentation upon one side in the form of semi-leaves, as indicated at E. The top B of the handle is plain and slightly 20 rounded. The base C is formed of the orna-

mented body part F, which unites with the lower portion of the body part A, and then swells downward and terminates in an ornamented ring or band G. The depressions D are slightly V-shaped, and the faces d of the 25 depressed portions may be of less surface than the other faces.

The handle is made of any suitable material.

Having now described my new design, what 30 I claim as new, and desire to secure by Letters Patent, is—

The design for umbrella or cane handles, substantially as herein described and shown.

In testimony of which invention I have here- 35 unto set my hand.

HENRY O. SCHMIDT.
